UNITED STATES PATENT OFFICE.

ARTHUR F. PYM, OF MARBLEHEAD, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON LASTS.

Application filed March 11, 1925. Serial No. 14,756.

This invention relates primarily to machines for operating upon lasts. The invention is herein illustrated as embodied in a machine for forming a plurality of positioning holes extending from the bottom face of a last and for inserting metallic bushings in the respective holes.

In two co-pending applications, Serial No. 698,099, filed March 10, 1924, and Serial No. 8,717, filed February 12, 1925, in the name of the present applicant, (now Letters Patent Nos. 1,674,059 and 1,674,060, respectively) are disclosed methods and machines relating to the lasting of the toe of a shoe, a characteristic of which is that a last, an insole and a lasting machine are each provided with a positioning surface, or with a plurality of positioning surfaces in spaced locations, preferably provided by positioning holes, by the use of which the last and the shoe upper materials, which are to be shaped thereon, may be positioned quickly and accurately in relation to the lasting devices.

One important object of the present invention is to provide a machine particularly adapted to form one or more positioning holes in the bottom of a last. A further object of the invention is to provide a machine for inserting metallic bushings in such holes. So far as applicant is aware, any machine adapted to perform these operations is new in the art.

With these and other objects in view, the preferred embodiment of the invention herein illustrated comprises the combination of a plurality of gages constructed and arranged to engage a last and thereby to determine its position in all directions, a plurality of drills for forming holes of predetermined depth in the bottom of the forepart of the last in predetermined relation to its edge contour and at a predetermined angle to the general plane of the bottom of said forepart, and also a plurality of tools for inserting bushings in the holes so formed and pressing the bushings into contact with the bottoms of such holes.

In the particular embodiment of the invention herein illustrated, the machine is constructed and arranged to form three positioning holes in predetermined, spaced relation to each other and to the contour of the last and then to insert a metallic bushing in each of said holes, the machine being thus

adapted for use in carrying out the method 55 claimed in application Serial No. 8,717 above referred to but it is within the scope of this invention to form one such hole only in each last, as is contemplated in the earlier application, Serial No. 698,099, also referred 60 to above. Moreover, the invention, in various aspects, is not limited to embodiment in machines of the type herein illustrated, by way of example, or to machines for performing the operations for which the illustrated machine has been especially designed.

The invention comprises also various other combinations and arrangements of parts, as well as particular features of construction, 70 which will now be described in detail in connection with the accompanying drawings which illustrate a preferred embodiment of the invention.

In the drawings:

Fig. 1 is an end elevation of the machine 75 with a portion of the frame broken away to show the parts behind it;

Fig. 2 is a side elevation with certain parts broken away and with a last shown in section;

Fig. 3 is a sectional plan substantially on the line III—III of Fig. 2 but with the clamp which engages the top of the last omitted;

Fig. 4 is a plan view of the two swinging 85 tool carriers with certain parts broken away and others shown in section;

Fig. 5 is an elevation partly in section of the bushing inserting mechanism, and

Figs. 6 to 9, inclusive, show details of construction hereinafter fully described.

Figs. 1 and 2 are on a slightly smaller scale than the other figures.

In the drawings, 10 designates the main frame or base of the machine upon which 95 rests a table 12 which carries the work gag- 100 ing and supporting devices and which is movable about a horizontal rod 14 so that the table and its associated parts may be raised bodily about the rod as a fulcrum to render the parts beneath readily accessible. A pair of pivotally connected links 15 limit 105 such movement of the table. Secured to the table is a bracket 16 in which are mounted certain last clamping devices to be described below. Set into a recess in the table over the bushing inserting tools, when they occupy the position shown in Figs. 2 and 4, is

a removable plate 18 in which are three holes 20, the plate being held in place in the table by two latches 22. Similarly, over the drills, when they occupy the position shown in Figs. 2 and 4, is set, in a recess in the table 12, a removable plate 24 also having fixed therein three bushings 26 and being secured firmly in position against movement either vertically or laterally by three clamps 28. These plates 18 and 24 are made readily removable in order that they may be replaced by similar plates in which the holes 20 and the bushings 26 respectively are differently spaced, as will be hereinafter explained.

L designates a last in the bottom of which positioning holes H are drilled by the present machine for the reception of metallic bushings B. It will be noted that the bottom of the forepart of this last is somewhat convex both longitudinally and laterally and, in order to position the last for these operations, gages are provided which engage both the bottom face of the last and also the surface of the last adjacent to its bottom in advance of the greatest transverse dimension of the last. These gages include a toe gage 32 secured to the table 12 and provided not only with a surface 34 to engage the bottom of the last adjacent to the toe but also with a slightly inclined surface 36 to engage the side of the last, as shown particularly in Fig. 5. The last positioning means includes also two pairs of side gages 38 and 40 (Fig. 3), in the form of levers, of which the pair 38 have, at their last engaging ends, two surfaces 42 and 44 similar to the surfaces 34 and 36 which engage respectively the bottom and the opposite sides of the last at substantial, and at approximately equal, distances from the toe gage. The gages, 40, engage the sides, but not the bottom, of the last also at substantially equal distances from the toe gage but nearer thereto than the gages 38 measured longitudinally of the last. These gages 38 are pivoted to the table 12 at 48 and are connected by a tension spring 50 which tends to maintain the rear ends 52 of the gage levers in contact with a wedge block 54 secured to a slide 56 in an undercut guideway 58 in the table 12, as shown in Fig. 8. The gages 40 are likewise held by a spring 60 outwardly so that rolls 62 mounted on the respective gages are maintained in engagement with tapering surfaces 64 of a block 65 secured to a slide 66 in another guideway 67 in the table 12. The two slides 56, 66 are connected by a comparatively heavy spring 68 which, when permitted so to do, draws them and the wedge blocks 54, 65 toward each other against the resistance of the lighter springs 50 and 60 so that the last engaging ends of the gage levers 38, 40 are at their minimum distances apart. The innermost positions of these

ends are determined by the adjustment of screws 72 (Fig. 1) threaded through the table, one for each pair of side gages. These screws respectively engage a pair of levers 74 fixed to rock shafts 76 in brackets 78 depending from the work table 12. Another pair of levers 79 also fixed to said shafts bear against surfaces 80, 82 forming parts of the slides 56, 66 respectively.

Thus by independent, preliminary adjustment of the two screws 72, the innermost positions of the ends of each pair of side gages 38, 40 will preferably be so adjusted that the distances between the ends of each pair will be less than the width of the last L at the corresponding distance from the toe end so that, when the last is inserted between them, it will be engaged by the ends of all four of the side gages before its toe end reaches the surface 36 of the toe gage 32. In so positioning the last, the operator insures that all four side gages shall contact with the opposite sides of the last, thus centralizing the last and locating it in a predetermined position angularly, longitudinally and laterally in the general plane of the bottom of the last. At the same time, the operator also presses the bottom of the last firmly against the three gaging surfaces 34, 42, 44 so as to predetermine the position of the last accurately in all planes normal to the bottom of the last.

To prevent any displacement of the last from this predetermined position while it is being clamped and while it is being operated upon, means illustrated particularly in Figs. 8 and 9, is provided for clamping or locking the slides 56 and 66 which control the position of the movable side gages 38 and 40. This clamping means is provided by undercutting the guideways 58 and 67, in which the correspondingly shaped slides 56, 66 move, and by plungers 88 movable vertically in the table and actuated to clamp the slides 56, 66 in their guideways through toggles 92, the lower end of each of which is pivoted to a bracket 94 depending from the table. These toggles and the plungers 88 are actuated through rods 95 (Fig. 9) connected to an equalizing lever 96 in turn connected by a link 97 to an arm 98 secured to a rock shaft 100 (Fig. 3) which in turn is mounted in bearings of a bracket 102 secured to the table 12. A horizontal arm 104 pinned to the rock shaft 100 is actuated through contact with a collar 106 loosely surrounding a rod 108 to which is fixed a collar 110, a compression spring 112 being interposed between the two collars. The rod 108 is pivotally connected to the lower end of a rack 114 movable in a guideway in a block 116 bolted to the bracket 16. This rack actuates a pinion 118 pinned to a short shaft 120 carried by the bracket 16 and having secured to it a bevel gear 122 which meshes

with another bevel gear 124 keyed to a short sleeve 125. This sleeve constitutes a nut through which passes a threaded rod 126 secured by a key 127 against rotation in its bearings in the bracket 16. Secured to the lower end of the rod is an abutment member 128 having a stab point 130 adapted to penetrate the upper surface of the toe portion of the last.

After the last has been located in predetermined position upon and against the gages 32, 38 and 40 in the manner above described, the abutment member 128 being then above its last clamping position shown in the drawings, the rod 108 is moved upwardly by mechanism about to be described so that the plungers 88 clamp the slides 56, 66 and thereby the side gages 38, 40 in their last engaging position, after which, through the continued upward movement of the rod 108 which is permitted by the compression of spring 112, the abutment member 128 is brought into contact with the forepart of the last, the stab point 130 penetrating the wood of the last so that the latter is clamped firmly in the position determined by the gages.

The said rod 108 is actuated in opposite directions by two treadles and connected mechanisms which will now be described. The rod is connected to a lever 131 by means, especially illustrated in Figs. 6 and 7, so arranged that the operator may readily disconnect the rod from the lever to enable the table 12 and the parts carried thereby, including the rod 108, to be raised, as above explained. This connecting means is provided by extending the lower end of the rod 108 between the forks 132 at one end of the lever 131, one of the forks of which is provided with a laterally extending boss 133. Passing through aligned holes 134 and 135 respectively in the forks 132 in the lower end of the rod 108 is a slidable pin 136 provided with a finger piece 138. Within a central blind hole 140 in the pin is a compression spring 142 bearing against the bottom wall of the hole and also against a plate 144 secured to the end of the boss 133 by two screws 146. The finger piece 138 slides in a slot 148 in the boss 133 which is provided with a shoulder 150. Normally, spring 142 maintains the pin 136 in the holes 134, 135, as shown in Fig. 6. When it is desired to disconnect the rod 108 from the lever 131, the pin 136 is retracted and turned slightly about its axis and then held in such retracted position by engagement of the finger piece 138 with the shoulder 150.

The lever 131 is pivoted at 156 to a block on a rod 204 further to be described and the rear end of the lever is connected by a rod 158 to the rear end of a treadle 160 through the actuation of which the rod 108 is depressed whereby the nut 125 is turned to

raise the abutment 128 and thus to unclamp the last. The rod 108 is raised and the nut 125 is turned in the opposite direction to clamp the last through another treadle 162 connected by a rod 164 to the lever 131 at 166 adjacent to the removable pin 136. The pitch of the thread upon the nut 125 and upon the rod 126 is relatively small so that the nut and screw are self-locking both in last clamping and also in last releasing positions.

The mounting of the tools, which include three drills 170 and three bushing inserting tools 172, and the mechanisms by which these tools are actuated will now be described. These drills are caused to bore three parallel holes H (Fig. 5) extending from the bottom face of the last L at a predetermined angle to the general plane of the forepart of the bottom of the last and then three metallic bushings B are forced to the bottoms of the holes so bored. Preferably these bushings are of slightly larger diameter than the holes so that they will be effectively retained in the last by friction after they have been forced into the holes. The general plane just referred to may be regarded as that determined by the surfaces 34, 42 and 42 of the gages 32, 38 and 38 and is substantially the plane determined by the horizontal line P, sometimes called the "floor line" of the last, shown in Fig. 5, the axes of the holes H being perpendicular to this plane. Moreover, as more fully explained in the companion application, Serial No. 8,717, above referred to, it is important that the bottoms of the holes H shall be located at definite, predetermined distances from this plane. Conveniently and as herein shown, the bottoms of all of the holes are at equal distances from this plane.

Furthermore, while it is contemplated that the holes will be located in the same relation to the edge contour of the last bottom and to each other in all lasts of the same size and style, and also that holes having the same relative spacing and arrangement may be employed in a substantial range of lasts of different sizes and styles, yet it is also contemplated that it will be desirable to have a greater spacing for the holes in a relatively large last than in a small last, and also that different spacings may be desired even for lasts of the same nominal size which are used for different types of shoes, such as welt and McKay shoes. Accordingly, provision is made, in the illustrated machine, for varying the relative spacing both of the drills 170 and of the bushing inserting members 172, as will later be explained.

Moreover, as is also pointed out in the companion application just mentioned and as shown in Fig. 5 of the drawings of the present case, the bushings B are provided

with blind holes h and, in order to carry out the method claimed in said companion application, it is important that the bottoms of these holes H shall be at a predetermined distance from the imperforate ends of the bushings B , said ends being located at a predetermined distance from the plane P , as above stated. Accordingly, in the use of the present machine, the holes H having been bored to a predetermined depth, the bushings B are forced into these holes with their ends engaging the bottoms of the holes. Preferably, therefore, the bushings B will be of such length that, after they have been seated in the holes H , their outer ends may be ground off flush with the bottom surface of the last.

The two sets of tools 170 and 172 are preferably carried on two laterally swinging carriers so that they may be swung alternately into precisely the correct operative position, shown in the middle of Fig. 2, immediately below the forepart of the last L after the latter has been accurately positioned in the machine in the manner already described.

The drills 170 are provided near their lower ends with enlarged portions having flattened surfaces 173 and shoulders 174 resting on loose washers 176 and their lower ends are internally threaded, respectively fitting the threaded upper ends of short vertical shafts 178 (Fig. 2) having shoulders against which the washers 176 are clamped as the drills are screwed on. The shafts are journaled in a block 180 which is removably secured by screws 181 to the upper end of a vertically slidable sleeve 182 and each shaft 178 is connected to another similar shaft 184, journaled in the lower portion of the sleeve 182, by universal joints and an extensible member, indicated at 186, which provides for the proper driving of the three shafts 178 even when their spacing from each other is varied according to the different spacings desired for the holes H in the last L , as above described. The three shafts 184 respectively carry three gears 188 which mesh with a vertically stationary gear 190 having a relatively wide face to provide for the proper driving of the gears 188 during their vertical movement with the drills. The gear 190 is mounted on a shaft 192 constituting the rotor of an electric motor indicated at 194. The shaft 192 also carries a fan 196 by which chips produced during the boring of the holes H in the last and dropping into a fan chamber 198 are expelled through an exit opening 200. The housing of the motor is firmly secured to a swinging frame or tool carrier 202 which is pivoted to swing in a horizontal plane upon a fulcrum rod 204 secured in bearings 206, 208 carried by the frame 10. The sleeve 182 and the drills 170 carried thereby may be

moved vertically by the operator through a bifurcated lever 210 pivoted at 212 to the frame 202 and having an operating handle 214. This lever is connected by links 216 to studs 218 screwed into opposite sides of sleeve 182.

To guide the drills and to restrain them against lateral springing, guide bushings 220 are provided which are fixed in a plate 221 that is removably secured in the upper end 75 of another vertically slidable sleeve 222. Flanges 223 integral with the bushings 220 bear firmly against the plate 221 and, by coming into engagement with the lower ends of the larger bushings 26 in the removable 80 plate 24, definitely limit the upward movement of the sleeve 222 and the parts carried thereby in which position the bushings 220 are preferably substantially flush with the upper ends of bushings 26 so that, whatever 85 the convexity of the last bottom, the ends of bushings 220 will not contact with it. The plate 221 rests upon an annular ledge 226 at the bottom of a recess in the upper end of sleeve 222 and is held against rotation therein by a key 224 (Fig. 4). Two spring pressed pins 225 entering slots 227 in the edge of the plate normally retain the plate in the recess and against the ledge but these pins may be retracted to permit removal of the plate 221, as for example, when it is desired to substitute a plate with bushings 220 differently spaced according to a different spacing of the holes H in the last. The sleeve 222 and the bushings 220 carried thereby are normally pressed upwardly by 90 two compression springs 230, their upward movement being normally limited by two latches 232 pivoted upon opposite sides of the sleeve 222 and normally held by springs 95 233 in engagement with lugs 234 projecting from the sleeve, only one such latch and one such lug being visible in Fig. 1. The studs 218 are slidable vertically in and fit the walls of slots 239 in sleeve 222 and also of slots 100 240 in a vertically fixed sleeve 242 which fits and guides both sleeves 182 and 222 and forms a part of the housing of the motor 194. Accordingly, the studs 218 and the sleeve 242 maintain both of the movable 105 sleeves 182 and 222 in a fixed angular relation with respect to the supporting frame 202.

With this construction, the drills 170 being rotated at high speed by the motor 194, the operator grasps the handle 214 and raises the drills from the position indicated in Fig. 1. During the first part of this upward movement, the sleeve 222 moves with the drills and carries the guide bushings 220 into the bushings 26, in plate 24 of the table 12, in which they have an easy sliding fit. These bushings 26, therefore, serve as guideways for the guide bushings 220. As soon as the bushings 220 have fully entered bush- 110 115 120 125 130

ings 26, any further movement of the bushings 220 and of the sleeve 222 is prevented by engagement of flanges 223 with bushings 26 and continued lifting pressure by the 5 operator upon the handle 214 causes the drills to bore the holes H in the last. The depth to which the drills penetrate the last is accurately determined by the adjustment of a screw 243 threaded into the top of block 10 180 and held in adjusted position by a lock nut 244. The distance which the ends of the drills 170 may move upwardly beyond bushings 220 is limited by the contact of the head of screw 243 with the lower surface 247 of 15 the plate 221. Hence, since the distance of the bottom of the last from the upper surfaces of the table 12, plate 24 and bushings 26—all of which surfaces lie in the same horizontal plane—is definitely determined 20 by the gage surfaces 34, 42 and since the ends of the drills 170 in their highest positions are likewise at definite distances from the same surfaces, the depths of the holes H formed by the drills are accurately pre- 25 determined.

The operator, by taking hold of a hand piece 245 connected with the latches 232 and by momentarily depressing the sleeve 222 against the resistance of springs 230, may 30 then swing the latches to the right, as shown in Fig. 1, disconnecting them from the studs 218 and he may then allow the springs to move sleeve 222 relatively to sleeve 182 so that the drills 170 are withdrawn from the 35 bushings 220 and so that accumulated chips may be cleared away from the drills and bushings.

Referring now in detail to the mechanism for inserting the bushings B in the holes H which have been bored by the drills 170, each tool 172, as shown more particularly in Figs. 2 and 5, comprises a vertically projecting pin 250 having at its base a shoulder 252 which supports a bushing B which has 40 been placed over the pin by hand or in any convenient manner when the tools 172 are in their uppermost position about to be described. The middle portion 254 of each tool 172 is of such diameter as to fit easily 45 the inner wall of the corresponding washer 26 in the plate 24. Each tool is provided with a shoulder 256 near its lower end to rest upon a block 258 into which a threaded portion 260 of the tool 172 is screwed. From 50 the block 258 depends a sleeve 262 which is 55 removably secured, as by a set screw 263, to the upper reduced end 264 of a vertical rod 268. The lower portion 270 of this rod 268 also has a reduced diameter, thus forming a shoulder 272 which rests upon the upper end 60 of another vertical rod 274 which fits over the portion 270 of rod 268 and is rotatable and slidable in lugs 276 of a swinging frame 65 278 which may turn upon a fixed rod 280 mounted in the frame 10 of the machine.

In its lowermost position, the block 258 rests upon the upper end of the frame 278 but it is vertically movable and rotatable in the frame. Clamped to the upper end of the rod 274 by a bolt 281 is a collar 282 while another collar 284 is clamped by a bolt 285 to the rod 268. A toggle 286 is pivoted at its upper and lower ends respectively to the collars 282, 284, being provided with a handle 288 by the actuation of which the operator may raise the block 258 and the bushing inserting tools 172 carried thereby to force the bushings B through the bushings 26 and into the holes H in the bottom of the last. 70

A relatively strong spring 290 connecting the two collars 282, 284 sustains the weight of rod 274 and normally maintains the toggle in the position shown in Fig. 5. A link 292 connecting collar 282 with a fixed collar 294 on the fixed rod 280, with the 80 frame 278, constitutes a "parallel motion" which, since rod 268 is keyed to both sleeve 262 and rod 274, maintains these parts and the parts carried thereby, including handle 288, always in the same angular relation to 85 the machine frame, whatever the position of the swinging frame 278, and thus insures the proper angular relation between the tools 172 and both the holes 20 and the bushings 26. While the spring 290 is strong enough 90 to sustain the rod 274 and its connected parts when the block 258 is in its lowermost position shown in Fig. 5, a support is provided for the lower end of the rod 274 in each of its two working positions. As shown particularly in Fig. 2, the lower part of the frame 10 of the machine includes two beams 296 into which are threaded two bolts 298 having flat heads 300 and lock nuts 302. These bolts are located immediately beneath 95 the rod 274 in its respective positions and are so adjusted that they are in contact, or just barely out of contact, with the lower end of the rod in such positions. Hence, when the frames 202, 278 are swung to the left as 100 shown in Figs. 2 and 4 to bring the tools 172 beneath the last as shown in Fig. 5, the rod 274 will be immediately above that one of the bolts 298 which is shown at the left in Fig. 2 and which will sustain the rod during 105 the relatively heavy pressure exerted thereon during the insertion of the bushings B. Clamps 308 may be provided also, as shown in Fig. 3, to hold table 12 down to the base 110 during this operation. 120

To insure further that the drills 170 and the bushings 220, when in their operative positions (Fig. 4), shall be in axial alinement with the bushings 26, the swinging frame 202 is provided with an extension 310 125 through a lug of which is threaded a stop screw 312 which will be so adjusted that, when its end comes into engagement with the vertical rod 280, the drills 170 will be in exact alinement with the bushings 26. Sim- 130

ilarly, the swing frame 278 is provided with two lugs 314 through which are threaded adjustable screws 316 which come into engagement with parts of the frame 10 of the machine and thus insure that the inserting tools 172 shall accurately aline alternately with the holes 20 and with the bushings 26.

The manner in which the illustrated machine may be operated to form positioning holes H in the bottom face of a last L and to insert bushings B in those holes has been indicated in connection with the foregoing detailed description but it will now be summarized. Most of the parts of the machine being in the positions indicated in Figs. 1, 2 and 4 but with the last and the bushings not yet placed in the machine, with the last clamping abutment 128 in its uppermost position and with the side gages 38 and 40 in their innermost positions determined by the adjusting screws 72, the upper portions of the three inserting tools 172 are lifted by handle 288 through the holes 20 in the plate 18 and three metallic bushings B are placed over the respective projections 250 and against the shoulders 252 after which the inserting tools are returned to their lowermost positions. Then a last L is placed by the operator with its bottom 30 against the surfaces 42 of the pair of side gages 38 and with the adjacent side portions of the last against the surfaces 44 and 46 of both pairs of gages 38, 40 and then the last is pushed inwardly, forcing the gages 38 and 40 apart and stretching spring 68, until the toe portion of the last has been brought firmly into engagement with both the surfaces 34 and 36 of the toe gage 32. While the last is thus held by the operator in this definite position heightwise relatively to the upper surfaces of table 12 and of plate 24 and also angularly, laterally and longitudinally relatively to the bushings 26, as determined by the three gage surfaces 45 contacting with its bottom and the five gage surfaces contacting with its toe and opposite sides adjacent to its bottom, the treadle 162 is depressed and the movable side gages are thereby first locked by the plungers 88 and then, through continued movement of the treadle, the abutment 128 is pressed against the upper portion of the toe of the last, the stab point 130 penetrating the last, so that the last is firmly clamped in said predetermined position.

The motor 194 having been started into operation so that the drills 170 are rotating at high speed, the handle 214 is moved upwardly by the operator to raise the inner sleeve 182 whereupon the outer sleeve 222 and the guide bushings 220 rise under the force of springs 230 until the flanges 223 of the bushings 220 come into contact with the lower ends of the bushings 26 at which time the upper ends of the

bushings 220 will be substantially flush with the upper ends of the bushings 26. Continued upward movement of the handle 214 causes the drills 170 to bore the holes H in the last, the distance to which the drills enter the last and consequently the depth of the holes H being determined by the engagement of the screw 243 with the surface 247 of the plate 221. The operator then returns the handle 214, the drills and the parts 70 movable therewith to their lowermost positions and shifts the swinging frame 202 to the left, as shown in Figs. 2 and 4, and also swings the other swinging frame 278 to the left into the position, determined by the left stop 316, wherein the inserting tools 172 are brought into alinement with the bushings 26 and with the holes H already formed in the last, as shown in Fig. 5. The operator then lifts handle 288, straightening 75 the toggle 286, and thus actuates the inserting tools 172 to force the bushings B into the holes H until they firmly bottom themselves therein, whereupon the inserting tools are again lowered to the position shown in 80 Fig. 5 and the swinging frames 202, 278 are returned to their initial positions shown in Fig. 4. The abutment 128 is then raised and the last released by the actuation of treadle 160 whereupon the last may be removed from the machine and the operation 85 repeated upon another last.

In case it is desired to adjust the machine for operating upon a last in which the holes H are spaced nearer together, further apart or otherwise differently from the spacing for which the machine is then set, the plates 18 and 24 are unclamped from the table 12 and are replaced by similar plates in which the holes 20 and bushings 26 are spaced according to the new spacing of the holes H to be formed in a last. The clamps 308 are released and the pin 136 is retracted from the holes 134, 135 so that the table 12 with the parts carried thereby may be swung about 100 the fulcrum rod 14 and held in raised position by links 15, leaving the parts below the table readily accessible. The plate 221 carrying the bushings 220 is released by the retraction of the spring pressed pins 225 105 and removed from the machine. The drills 170 are unscrewed from the upper ends of the driving shafts 178 and the screws holding the block 180 in the sleeve 182 are removed so that this block may be removed 110 from the machine and replaced by a similar block in which the journals for the driving shafts have a spacing corresponding to the new spacing for the holes H to which the machine is being adjusted. Because of the 115 universal connections between shafts 178 and 184, the shafts 178 can readily be inserted in their journals in the new block 180 after which the drills 170 are again screwed on 120 to the threaded ends of the shafts 178. A 130

new plate 221, having bushings 220 fixed therein according to the new spacing of the holes H, is now set in place and secured in the recess in the upper end of the sleeve 222 by the spring pressed pins 225 and the key 224. The block 258 with its integral sleeve 262 and with its inserting tools 172 is lifted by handle 288 and, set screw 263 having been loosened, the block and tools are removed from the machine and are replaced by similar parts in which the tools 172 are arranged according to the new spacing. The table 12 is then lowered and clamped to the base 10, rod 108 is connected by pin 136 to lever 131 and the machine is ready for operation again.

Having fully described my invention, what I claim as new and desire to secure by Letters Patent of the United States is:

20 1. A machine for forming in the bottom of a last positioning holes located respectively near the toe and near the opposite sides of the forepart thereof having, in combination, a support, a toe end gage and two 25 pairs of side gages at substantially different distances from the toe gage measured longitudinally of the last, said gages being carried by said support and being constructed and arranged to engage the bottom and sides 30 of the forepart of a last in advance of its greatest transverse dimension and to locate it in predetermined position longitudinally, laterally and angularly relatively to said support both in the general plane of the bottom 35 of the last and also in a direction transversely to said plane, a plurality of drills located in predetermined relation to said gages, and means for actuating the drills to form holes in the bottom of the last.

40 2. In a machine for operating on lasts, the combination of a single gage support, an end gage and a plurality of pivoted side gages carried by said support and constructed and arranged to engage a last both 45 at three separated points in its bottom and also at one end and at two separated points longitudinally of each side of the last in advance of its greatest transverse dimension, yielding means tending constantly to press 50 opposite side gages toward each other, means for adjustably determining the initial position of said side gages, and a drill located in predetermined relation to said gages and movable toward and from said support for 55 forming a positioning hole in the bottom of the last in predetermined relation to its edge contour and at a predetermined angle to the general plane of the bottom of the last.

3. In a machine for operating on lasts, the 60 combination of a fixed toe gage and a plurality of spring pressed side gages constructed and arranged to engage the bottom and the side edges of the forepart of a last near its bottom and at separated points longitudinally thereof to locate the last in pre-

determined position in the general plane of the bottom of the last and also angularly relatively to that plane, means for locking said side gages in last-engaging position, a clamp engaging the curved surface of said 70 forepart for securing the last in the position determined by said gages and a plurality of tools constructed and arranged to operate in predetermined locations upon the bottom of the forepart of the last while the latter is so 75 located.

4. In a machine for forming in the bottom of a last three positioning holes located respectively near the toe and near the opposite sides of the forepart thereof and adapted for 80 use in locating the last accurately for a subsequent shoe-making operation, the combination of a support, a fixed toe gage and two pairs of connected, inwardly spring-pressed, side gages located at substantially different 85 distances from the toe gage, the toe gage and those of the two side gages which are located farthest from the toe gage having surfaces to engage both the bottom and the sides of the forepart of the last and all of 90 said gages cooperating to locate the last in predetermined position longitudinally, laterally and angularly relatively to said support both in the general plane of the bottom 95 of the last and also in a direction transversely to said plane, a clamp engaging the curved surface of the forepart of the last, means for actuating the clamp to hold the last securely in the position determined by 100 said gages, three drills located in predetermined relation to said gages and to each other, and means for actuating said drills to form said positioning holes in predetermined relation to the edge contour of the last and at a predetermined angle to the general 105 plane of the bottom of the last, including means for determining the depth of all three holes measured from the plane determined by the bottom engaging surfaces of said gages.

5. A work positioning device having, in combination, an end gage, two pairs of pivoted side gages, means including a pair of wedge blocks and a spring acting upon the two pairs of gages to cause said gages yieldingly to engage work, presented thereto, at substantially different distances from the end gage for determining the position of the work longitudinally, laterally and angularly in a plane, and means for adjusting independently the initial position of each pair of gages.

6. A work positioning device having, in combination, two pairs of pivoted side gages, a pair of slide blocks, cam members thereon for moving the respective pairs of gages, and means yieldingly connecting said blocks to equalize the pressure of the gages against the work.

7. A work positioning device having, in 130

- combination, a plurality of gages, yielding means for pressing the gages against the work, a clamp for securing the work in the position determined by the gages, means for locking the movable gages in work engaging position, and actuating means constructed and arranged to operate first the gage locking means and then the work clamping means.
10. 8. A work clamping mechanism having, in combination, a work engaging member, a self-locking screw and nut through which said member may be moved toward and from the work, and devices for relatively 75 rotating said screw and nut in opposite directions including two actuating levers and separate connections therefrom to a common connecting member.
9. In a machine for operating on lasts, the combination of a frame, a tool supported by the frame, a work support movable relatively to the frame to render the tool readily accessible, work positioning devices mounted on said support, actuating devices therefor 80 mounted on the frame, operative connections between said actuating devices and said positioning devices, and a removable member forming part of such connections by the removal of which said connections are broken 85 and thus rendered inoperative to permit movement of said work support relatively to said frame.
10. In a machine for operating on lasts, the combination of a toe gage and two pairs 90 of side gages at substantially different distances from the toe gage constructed and arranged to engage the bottom and the side edges of a last, to locate the last and determine the plane of the last bottom, a plurality 95 of drills for forming holes simultaneously in the bottom of the forepart of the last, means for determining the depth of said holes with reference to said plane, a plurality of tools for first supporting and then inserting simultaneously bushings in the respective 100 holes and pressing them into contact with the bottoms of said holes, said drills and tools being movable alternately into the same operative position with relation to the 105 last.
11. In a machine for operating upon lasts, the combination of a plurality of gages to engage the bottom and the side edges of a last to determine its position in all directions, a clamp for securing the last in the position thus determined, and bushing inserting tools constructed and arranged to support a plurality of bushings and being movable in lines substantially normal to the 110 general plane of the bottom of the last to force the bushings to the bottoms of holes already formed in the bottom of the last.
12. In a machine for forming positioning holes in the bottoms of lasts, the combination 115 of a plurality of gages constructed and arranged to engage the bottom and the side edges of a last at separated points longitudinally thereof to determine the position of the last in all directions, means for clamping the last in the position thus determined, 70 a plurality of drills, a movable bushing constituting a lateral guide for each drill and normally engaging the drill close to its operating end, means by which the drills and the bushings, while maintained in such relation, may be moved together to a position close to the bottom of the last and by which the drills may then be moved further to form holes in the bottom of the last.
13. In a machine for forming positioning 80 holes in the bottoms of lasts, the combination of a last support having a guideway, gaging devices for determining the position of a last in all directions relatively to said support and to said guideway, a drill, a 85 movable bushing constituting a lateral guide for the drill and normally engaging it close to its operating end, means for maintaining said drill, bushing and guideway in alignment, yielding means tending to move the 90 bushing axially along the drill, and means by which the drill and bushing may be moved together first toward the last and thereafter independently for a predetermined distance to form a hole of predetermined depth in the last.
14. In a machine for forming holes in the bottoms of lasts, the combination of a last support having a guideway, gaging devices 100 for determining the position of a last relatively to said guideway, a drill, a moveable bushing constituting a lateral guide for the drill and normally engaging it close to its operating end, means by which the drill and bushing together may be moved to a position close to the bottom of the last with the bushing in said guideway, and means for positively limiting the movement of the drill 105 with relation to and beyond the plane of the bottom of the last.
15. In a machine for forming holes in the bottoms of lasts, the combination of a last support having a plurality of guideways, a plurality of drills, a movable bushing constituting a lateral guide for each drill, 110 means for maintaining the respective drills, bushings and guideways in alignment, and means by which the drills and the bushings may be moved longitudinally into and out of the guideways.
16. In a machine for forming holes in the bottoms of lasts, the combination of last positioning means, a drill, a movable bushing constituting a lateral guide for the drill, yielding means and latching devices to maintain the end of the drill normally within the bushing, said devices being shiftable to change the position of the drill relatively to the bushing.
17. In a machine for operating on the 115

bottoms of lasts, the combination of last positioning means, a plurality of sets of tools comprising a set of drills and a set of bushing inserting tools, a holder for the set of 5 drills and a holder for the set of inserting tools, said holders being readily removable with their respective tools from the machine to provide for the substitution of holders in which the tools have a different spacing relatively to each other, and actuating devices for said tools constructed and arranged to maintain their connection with said tools for all of such different spacings thereof.

10 15. 18. In a machine for forming holes in the bottoms of lasts, the combination of a last support having a plurality of guideways, a

plurality of gages on said support constructed and arranged to engage the bottom and side edges of a last, a plurality of drills 20 movable into and out of alignment with said guideways, means for rotating said drills at high speed, means by which said drills may be moved through said guideways to form simultaneously a plurality of holes in the 25 bottom of a last, and means by which said drills may be located positively in alignment with said guideways and in predetermined relation to the contour of the last as positioned by said gages.

In testimony whereof I have signed my name to this specification.

ARTHUR F. PYM.
